DESCRIPTION

FIG. 1 is a top perspective view of a cartridge for use in an injection device in accordance with our new design;

FIG. 2 is a front elevation view thereof;

FIG. 3 is right elevation view thereof;

FIG. 4 is a rear elevation view thereof;

FIG. 5 is a left elevation view thereof;

FIG. 6 is a top plan view thereof; and,

FIG. 7 is a bottom plan view thereof.

The features shown in broken lines depict environmental structure only and form no part of the claimed design.
